S. CAROSELLI

NECKTIE

Filed April 28, 1926

Silvio Caroselli, INVENTOR.

BY J. S. Thomas

ATTORNEY.

UNITED STATES PATENT OFFICE.

SILVIO CAROSELLI, OF DETROIT, MICHIGAN.

NECKTIE.

Application filed April 28, 1926. Serial No. 105,091.

My invention relates to an improvement in scarfs or neckties shown in the accompanying drawings and more particularly described in the following specification and 5 claims.

The purpose of the present invention is to improve the construction of the scarf shown in my Patent Number 1,282,042 issued October 22nd, 1918.

10 As in the construction shown in my former patent, the present tie is designed to be opened in the back that it may be pressed from the inside when wrinkled through wear.

Heretofore it has been customary in making four-in-hand ties to insert a padding or lining of canton flannel or other suitable material to give the tie the "fullness" necessary to produce a pleasing effect when worn and in accordance with the usual custom in 15 neckwear not designed to be "opened" the lining consists of a padding inclosed within the silk fabric forming the tie. This lining however, frequently becomes misplaced beneath the covering of silk producing a 20 "bunched-up" appearance and if pressed while in that condition the tie is apt to be permanently injured through creasing.

In my former invention a lining extending from edge to edge of the tie was provided to 30 give the required "fullness" and to insure against creasing, the marginal edges of the lining were stitched beneath a binding strip or beneath the marginal folded edge of the silk forming the tie.

35 While this manner of constructing the tie disposed of the objectionable feature of the lining becoming displaced, it has been found in practice that owing to the difference in the material forming the outer covering and that of the lining they would not "stretch" uniformly and upon applying a pressing iron to the lining the covering silk was apt to be creased, thereby ruining the latter.

40 The primary object of the present invention is therefore to construct a tie which may be readily opened at the back for pressing, the lining being divided into two strips spaced apart and respectively attached to the inwardly turned marginal edges of the tie, thereby supplying the required "fullness" necessary to produce a pleasing effect but leaving the central longitudinal portion of the tie—being that portion exposed when 45 worn—unlined so that it may be readily pressed upon applying an iron directly to the

back of the silk forming the tie, insuring a smooth unwrinkled outer surface.

With the foregoing and other objects in view the invention further consists in 60 other details of construction hereinafter described and claimed it being understood that changes may be made in the precise embodiment of the invention shown in the drawings without departing from the spirit of the 65 same.

In the drawings accompanying this specification:

Figure 1 is a fragmentary elevation of a 70 four-in-hand tie as viewed from the back showing the usual overlapping folded edges at the back opened to expose the lining or strips of padding secured to the respective folded portions.

Figure 2 is a fragmentary elevation of 75 the tie shown in the preceding view with the detachable edges folded and secured together as when worn.

Figure 3 is a cross-sectional view on line 80 3—3 Fig. 1.

Referring to the reference letters upon the drawings:

A denotes a four-in-hand tie of usual 85 shape with its overlapping edges B, B at the enlarged end of the tie detachably connected together at the back with snap fastening device C of usual construction.

The overlapping edges B, B are divided by a transverse cut B¹ at the back adjacent the narrow neckband D connecting the wide 90 end B^a with the relatively narrower end D^a,—the latter when worn being concealed beneath the former.

E, E indicate strips of canton flannel or 95 other suitable material spaced apart and respectively sewed beneath a binding strip to the marginal edges of the enlarged overlapping folded ends B, B of the tie,—the inner edges of the strips may be loose or "blind-stitched" to the silk fabric adjacent 100 to the creases resulting from folding the ends B, B back upon the longitudinal central portion or body of the tie. The longitudinal central portion of the tie is unlined when opened and therefore it may be pressed 105 from the back without danger of wrinkling or creasing the fabric.

The inwardly folded edges of the tie may also be pressed through the lining and as 110 these strips may be loose on one edge or "blind-stitched" to the outer fabric the lining may be readily stretched to adjust it.

self to the outer fabric and thereby avoid wrinkling or creasing the latter when pressed, but if a crease should occur in the inwardly folded edges B, B when folded in overlapping relation and secured by the snap fasteners it will be concealed when the tie is worn.

Having thus described my invention what I claim is:

- 19 1. In a scarf; a tie fabric folded longitudinally to provide a medial longitudinal central portion with folded marginal portions overlapping each other and the back of the central medial portion; a lining comprising two strips of fabric respectively secured to the edges of the marginal overlapping portions and extending in a transverse direction from each edge of the latter only to the creases formed in the tie fabric bond-
- 15

ing the sides of said longitudinal medial portion.

2. In a scarf; a tie fabric folded longitudinally to provide a medial longitudinal central portion with the folded marginal edges overlapping each other and the back 25 of the central medial portion; a lining comprising two strips of fabric respectively secured to the edges of the marginal overlapping portions and extending in a transverse direction from the edges of the latter to the 30 creases in the tie fabric bonding the sides of said longitudinal medial central portion, the inner spaced edges of said lining being "blind-stitched" to the tie fabric along the line of said creases.

In testimony whereof I sign this specification.

SILVIO CAROSELLI.
